ATTORNEY

UNITED STATES PATENT OFFICE.

ALFRED CROSSLEY, OF WASHINGTON, DISTRICT OF COLUMBIA, ASSIGNOR TO WIRED RADIO, INC., OF NEW YORK, N. Y., A CORPORATION OF DELAWARE.

RADIOFREQUENCY CHOKE COIL SYSTEM.

Application filed July 20, 1926. Serial No. 123,785.

My invention relates broadly to the construction and the mutual arrangement of choke coils that offer a maximum impedance over a broad band of frequencies.

5 One of the objects of my invention is to provide a construction of a choke coil system employing a series of choke coils arranged to offer a maximum impedance over a broad band of frequencies.

10 Another object of my invention is to provide a construction of a choke coil system in which a plurality of choke coils constitutes the system, each choke being designed to be equal in resonant frequency condition 15 to that of the other coils for securing maximum impedance over a broad band of frequencies.

20 A further object of my invention is to provide a choke coil system having a greater inductance and a less distributed capacity than it has heretofore been possible to obtain.

25 Still another object of my invention is to produce a choke coil arrangement which will have greater impedance over a broader band of frequencies than it has heretofore been possible to obtain with any known single choke coil.

30 My invention will be more clearly understood from the following specification and by reference to the accompanying drawings, in which:

35 Figure 1 is a graph of the characteristic reactance curve of a choke coil as used in the circuit arrangement of a high frequency oscillator system; Fig. 2 is a side elevation illustrating one arrangement of the multiple choke coil system of my invention; Fig. 3 is a graph showing the characteristic reactance curve of the multiple choke coil system 40 illustrated in Fig. 2; and Fig. 4 shows a modified arrangement of choke coils employed in the system of my invention.

45 I have found that a single layer, banked wound or pancake type of choke coil is limited from a high impedance standpoint to a narrow band of frequencies. I have also observed in the operation of high frequency electron tube oscillator circuits that these 50 types of choke coils possess certain qualities that render them dangerous in operation at certain frequencies. Many cases have been recorded where the coils were actually destroyed due to their low impedance at certain

frequencies. Tests show that single choke coils have very low impedance values at frequencies slightly less than two, four, or six times their fundamental resonant frequency.

55 Inasmuch as single choke coils are very seldom operated at frequencies greater than twice the resonant frequency of the coil it will be best to consider their characteristics over a range from one-half to twice the resonant frequency of the coil. Considering the 60 choke coil from an impedance standpoint, all choke coils are parallel electrical circuits having inductance and capacity, the capacity being that of the distributed capacity of the coil. This distributed capacity is the summation of the capacities between turns, between inner and outer layers and that capacity which exists between the coil and grounded objects. This condition exists in the universal wound or pancake types of 65 coil, which types are particularly suited for 70 choke coil use.

75 The parallel combination in the choke coil therefore permits maximum impedance to currents of a frequency equal to that of the resonant frequency of the coil, and a decrease in impedance for frequencies above and below the resonant frequency. Upon closer study of the choke coil, especially 80 when it is considered that one end of the coil is always at ground potential, it will be noted that it has characteristics that resemble those of an antenna. An antenna has maximum capacity and inductance at its base 85 and minimum inductance and capacity at its top. A choke coil grounded at one end, preferably the outer end in the universal wound type, has maximum capacity and inductance at this outer end and minimum inductance and capacity at the inner terminal. 90

95 Again comparing the choke coil with the antenna, it will also be found that it has resonant conditions other than that of the fundamental of the choke coil, that is to say, 100 at harmonic frequencies of the fundamental there are resonant conditions. Thus at double, quadruple and other even multiple frequencies the choke coil has a series resonant condition, while at third, fifth and seventh multiple frequency, there is a parallel resonant condition. This effect is further illustrated by reference to the reactance curve shown in Fig. 1. In this figure, the 105

numerals along the frequency line or abscissae indicate the multiple frequency relationship; in other words, 1 is the fundamental or first resonant frequency period of the 5 choke coil while 2 represents double frequency and so on.

By reference to the reactance curve in this figure, it will be noted that at the first, third and fifth frequency points, parallel resonance is obtained. This condition of parallel resonance indicates maximum impedance and therefore for best choking effect it is necessary to operate the choke coil at or near the point of parallel resonance. 10 Again referring to the reactance curve, it will be observed that at the second and fourth multiple frequencies there is a series resonant condition. These conditions are the danger points in a choke coil. In other words, under these conditions the reactance is 15 zero and all that remains is the circulating resistance of the choke coil which is of low value. At parallel resonance the reactance is zero, but the resistance is infinite it being equal to 20

$$\frac{\omega^2 L^2}{R}$$

where L is the inductance of the coil and R 30 is the circulating resistance of the circuit.

In view of the conditions obtaining in a single choke coil it is therefore good practice to operate the coil over a range of frequencies from one-half to one and two-thirds times its resonant frequency. 35

Having thus explained the characteristics of a single choke coil, I will now describe my invention wherein I employ a number of choke coils and thereby obtain greater 40 impedance over a broader band of frequencies than is obtainable with any single type choke coil.

The first type of choke coil that I employ consists of two or more coils of identical 45 characteristics placed at such distance from each other that there is no appreciable magnetic or electrostatic coupling between them, and these coils are connected in series with each other as shown in Fig. 2. In this figure, 1, 2 and 3 are the coils that are attached to a bakelite supporting rod 4. This rod is maintained in a fixed position by the supporting members 5.

The electrical characteristics of such a 55 choke coil assembly may be described as follows: It may be assumed that the resonant frequency of each coil is equal to the fundamental frequency 1 shown in Fig. 1. Inasmuch as there are three coils in series with 60 no magnetic coupling between them, the total inductance of the combination must be three times that of one coil while the capacity of the series is one-third that of one coil. From this condition it follows, 65 therefore, that the reactance must be three

times that of one coil and inasmuch as the inductance-capacity product is the same, the resonant frequency condition is equal to that of one coil.

To further illustrate the reactance values, 70 the effect of three coils as compared with one coil may be seen in Fig. 3. In this figure two reactance curves are shown, the dotted line curve indicating the reactance of the single coil over the frequency range, 75 while the full line curve indicates the reactance of the three coils in series.

The operation of these three coils at the series resonant frequencies, second, fourth, and higher, will not be dangerous as the 80 operation of a single coil as the reactance, and consequently the resistance at any of these frequencies, will be at least three times as great as that of one coil. Under practical operating conditions I have found that the 85 impedance at or near the even multiple frequencies is even greater than theoretical conditions would indicate.

I therefore obtain with my multiple coil arrangement a greater impedance over the 90 same frequency range and have secured such an increase in the impedance at the danger points as to render the choke coil usable at these points. This may be appreciated when it is pointed out that the resistance at the 95 danger point for one well designed coil is very seldom less than 10,000 ohms.

It becomes necessary under special circumstances to reduce the size of the choke coil and for this reason the condition of zero-coupling between coils may be dispensed with. To meet this need I may arrange the coils and place them in such position that magnetic and electrostatic coupling between 100 coils is effected.

This modified arrangement produces a choke coil that has a lower fundamental frequency than that of one coil, but still has a high impedance over a broad band of frequencies. Such a choke coil system is shown 110 in Fig. 4. The arrangement of the coils permits the mutual inductance of the coils to add to the inductance of the three coils, i. e., the inductance of this arrangement is approximately quadruple the inductance of one coil. The capacity of this arrangement is not one-third the capacity of one coil but is only slightly lower than that of one coil. This combination produces a choke 115 coil of large inductance and small capacity, a condition that cannot be obtained with any single coil, particularly when relatively large size wire is employed.

This type of choke coil has at least twice the inductance and two-thirds the capacity of the best type commercial choke heretofore known to the art, with the additional features of three times the impedance at the 125 danger frequencies.

It is important that coils of the same size 130

be used throughout my arrangement. If different size coils are employed additional series resonance conditions or dangerous points will be obtained at frequencies half way between the fundamental resonant periods of the respective coils. This is particularly true when two coils are employed.

Referring to Fig. 4 in detail, reference character 6 represents a bakelite or glass rod that fits into a brass base or socket 7. The coils 2 and 3 slide down over the rod 6 and are separated from each other by bakelite or glass separators or bushings 9. A securing piece 10 fits over the top of rod 6 and by means of screw 11 holds all the coils in place. A metal connector 12 under screw 11 acts as a connector for the high potential terminal of the choke coil 1. The choke coil 1 is fixed in position on rod 6 between the upper bushing 9 and the retaining cap 10. The coils 1, 2 and 3 are connected as shown, that is, the outer terminal of coil 1 to the inner terminal of coil 2, and the outer terminal of coil 2 to the inner terminal of coil 3. The outer terminal of the last coil 3, connects direct to the low potential terminal 14 on socket 7. This terminal is made fast to the brass base 7 by a screw 15. For insulating the high voltage direct current source, a porcelain or pyrex insulator 16 is employed. Connection is made to the insulator by the threaded end of the base 7 that screws into the insulator.

The special relation of the coils 1, 2 and 3 may be properly selected for securing the most desirable results and the relation permanently fixed for the band of frequencies over which the oscillator is designed to be operated.

The action of the plurality of choke coils has been illustrated in Fig. 3. The reactance characteristic of the plurality of coils connected in series shows a substantial increase over the working frequency range as compared to the reactance of a single choke coil. At the same time the resistance has been increased at least three times over that of a single choke coil thereby eliminating the tendency of the choke coil to be destroyed at resonant frequencies. The fact that the individual coils are series connected in the particular manner shown, substantially reduces the distributed capacity.

While I have described my invention in certain preferred embodiments, I desire that it be understood that modifications may be made and that no limitations upon my invention are intended other than are imposed by the scope of the appended claims.

What I claim as new and desire to secure

by Letters Patent of the United States is as follows:

1. A choke coil system comprising a plurality of choke coils each having small distributed capacity arranged to have substantially no magnetic or electrostatic coupling between said coils except that coupling which is due to conductive connection and a series connection between said choke coils for securing a relatively high reactance over a selected band of frequencies.

2. A choke coil system for high frequency electrical currents comprising a plurality of individual choke coils each designed to have small distributed capacity and each arranged with respect to another with substantially negligible magnetic and electrostatic coupling therebetween and a series connection between said coils, the outer terminal of one coil being connected with the inner terminal of a succeeding coil whereby the reactance of said coils over a selected band of frequencies is relatively large while the distributed capacity of said coils is relatively small.

3. A choke coil system comprising a plurality of individual choke coil units each arranged to have relatively small distributed capacity, means for mounting said units with respect to each other in such manner that there is no appreciable magnetic or electrostatic coupling therebetween, a series connection between said units, a high potential terminal located at the inside of one of said units and a low potential terminal located at the outside of another of said units, said last mentioned units being separated from said first mentioned coil by at least one other of said coils.

4. A choke coil system comprising in combination a plurality of choke coil units each arranged to have small distributed capacity, means for mounting said choke coil units with respect to each other in such manner that there is no appreciable magnetic or electrostatic coupling therebetween, a series connection between said plurality of coils with the outer terminal of one coil connected to the inner terminal of a succeeding coil with the terminals of said choke coil system across the inside of one of said choke coils and the outside of another of said choke coils for substantially increasing the resistance of said choke system at resonant frequencies for preventing the destruction of said choke coil system at said resonant frequencies while maintaining the distributed capacity of said choke coil system at a low value.

ALFRED CROSSLEY.
